Fred D. Jones
ATTORNEY

UNITED STATES PATENT OFFICE.

JOSEPH BORGLIN, OF SEATTLE, WASHINGTON.

TYPE-WRITER.

1,822,224.

Specification of Letters Patent. Patented Nov. 18, 1919.

Application filed October 17, 1918. Serial No. 253,603.

To all whom it may concern:

Be it known that I, JOSEPH BORGLIN, a citizen of the United States, residing at Seattle, in the county of King and State of Washington, have invented certain new and useful Improvements in Type-Writers, of which the following is a specification.

This invention relates to improvements in typewriters and has for its principal object to provide an improved and novel device for automatically returning the carriage to normal position.

The primary object of the invention is to provide simple and economical electrical means which when the carriage reaches the end of a line a circuit will be closed, and the carriage will be automatically returned to normal position.

In the accompanying drawing:—

20 The figure represents diagrammatically a portion of a typewriter, and a carriage with the improved mechanism applied thereto.

Referring more particularly to the drawings, numeral 1 indicates the frame work of a typewriter upon which is mounted a carriage 2 which carries a platen roll 3. In order to bring the carriage 2, back to its normal position, I provide a solenoid 18, and 25 a coöperating armature 19 mounted upon a pivoted lever 20. Lever 20 extends vertically beyond the solenoid and is connected by a bar 21 to the vertical arm, of a bell crank lever 22, which is pivoted to the frame 30 of the machine 1. A cord 23 is connected to the horizontal arm of the bell crank lever 22, said cord being trailed over a pulley 24, and at its end it is connected to the carriage 2. The opposite end of the carriage 2 is provided with a contact 25, which is 35 adapted to engage another contact 26, located on the frame 1, at the end of the travel of the carriage. The engagement of the contacts 25 and 26, closes a circuit 27 in 40 which is a battery 28, the circuit leading to the solenoid 18.

When the solenoid is energized it attracts

the armature 19, thus drawing the levers 20, and 22, toward it, thereby drawing upon the cord 23, sufficient to pull the carriage 50 back to normal position. It will be understood that the mechanism for returning the carriage operates automatically, and is therefore independent of the operation of the keys.

55 While I have shown a particular form of embodiment of my invention, I am aware that many minor changes therein will readily suggest themselves to others skilled in the art without departing from the spirit and scope of my invention and I therefore desire to avoid being limited to the exact form described.

Having described my invention, what I claim as new and desire to protect by Letters Patent, is:—

In typewriter mechanism, a frame, a carriage to slide thereon, a pulley connected with one end of the frame, a bell crank lever having a long arm and a short arm 70 and pivotally connected with the frame, said long arm extending toward the pulley and arranged beneath it for vertical movement toward and away from the same, a flexible element secured to the free end of the long arm and passed about the pulley and attached to the carriage, a vertically swinging lever arranged near and beneath the opposite end of the frame, means for pivotally supporting the lower end of the 75 vertically swinging lever, an electro-magnet arranged upon one side of the lever near its pivot point with the lever extending beyond the electro-magnet for a substantial distance, a rod pivotally connected with the 80 free end of the vertically swinging lever and with the free end of the short arm, said electro-magnet located in an electric circuit and means to close the circuit when the carriage has moved to the end of its 85 travel in one direction.

In testimony whereof I affix my signature.

JOSEPH BORGLIN.
